UNITED STATES PATENT OFFICE.

SAMUEL V. TENCH, OF WILKES-BARRE, PENNSYLVANIA.

RAIL-BENDER.

1,355,713.

Specification of Letters Patent. Patented Oct. 12, 1920.

Application filed December 13, 1919. Serial No. 344,573.

To all whom it may concern:

Be it known that I, SAMUEL V. TENCH, a citizen of the United States, residing in Wilkes-Barre, Luzerne county, Pennsylvania, have invented new and useful Improvements in Rail-Benders, of which the following is a specification.

Those forms of rail benders now on the market, with which I am familiar from having used the same, are subject to several disadvantages.

In the first place, owing to the excessive friction and resistance developed, they generally require the services of two men to operate them, when rails of all but the lightest weights are being treated.

Furthermore, the threads of the plunger break or strip where the strain is borne in the head of the usual U-shaped frame.

In addition, the presser foot on the operating end of the plunger wears out quickly, due to the friction between the plunger and foot, and frequently breaks off in bending operations, because of its improper relation to the plunger.

The objects of my invention are to reduce or minimize the friction heretofore developed in the operation of rail benders now on the market, whereby a single operator can readily manipulate the bender in working upon rails of any usual weight; to so assemble the plunger and its presser foot that the breakage of a foot or of a plunger can readily be repaired by substituting a new part for the broken one without necessitating the discard of the entire plunger and foot; and to so proportion the parts that no strain in a direction axially of the plunger is sustained by the means which connects the plunger and presser foot for relative rotation.

Still other objects, among which is the reduction in wear between the parts, will be more fully explained hereinafter and particularly pointed out in the claim.

In the accompanying drawings, Figure 1 is a side view of a rail bender equipped with my invention;

Fig. 2 is a longitudinal sectional view, through the presser foot and a part of the plunger;

Fig. 3 is a transverse sectional view, showing one means for connecting the foot and plunger for relative rotation;

Fig. 4 is a detail sectional view of an antifriction bearing; and

Fig. 5 is a fragmentary detail view, showing the means connecting the plunger and foot.

In effecting my invention, I employ the usual substantially U-shaped frame, formed of opposed arms or branches 1 diverging from a head 2. The free ends of the arms or branches carry hooks or lips 3, to engage the flange of the rail to be bent, it being understood that the device is equally applicable for forming curves in rails and for straightening curved or bent rails.

The head 2 is bored and threaded in the usual manner to accommodate the screw plunger 4, which may be turned in either direction by any convenient means, as by a cross bar 5.

The plunger 4 extends into the space embraced between the arms 1, and carries a presser foot 6, and it is herein that my invention resides.

The inner end of the presser foot 6 is axially recessed, as at 7, to form a socket, and the operating end of the plunger 4 is reduced, as at 8, and entered in the socket in the presser foot.

In order to relieve the friction which would be developed by the rotation of the inner end of the reduced portion 8 of the plunger against the bottom of the socket 7, I interpose a reversible antifriction bearing between such inner end and the bottom of the socket. Conveniently, the antifriction bearing may include a pair of opposed races 9, 9, between which are confined the rolls or balls 10, the lower race being seated upon the bottom of this socket and the inner end of the reduced portion 8 resting against the upper race.

The antifriction bearing thus forms a thrust-sustaining member for the plunger, and permits an unobstructed rotation of the latter relatively to the presser foot. A bolt or other fastening means 11 passes axially through the races 9, 9, to secure them together against accidental separation, and to hold the balls in place, and converts the bearing into a unitary element which is readily dropped into and loosely seated in the socket 7 prior to the insertion of the reduced end 8 therein, and as easily removed after the withdrawal of the reduced end 8.

The bearing is made reversible to present a new thrust-sustaining surface to the reduced end of the plunger, if necessary.

- The depth of the socket 7, the length of 5 the reduced portion 8, and the thickness of the antifriction bearing are so related that the shoulder 12, formed at the juncture of the reduced portion 8 with the threaded portion of the plunger 4, is spaced apart 10 from the upper end of the socket to form a clearance, as shown in Fig. 2, whereby to eliminate friction between the rotatable plunger 4 and the stationary presser foot 6 at this point.
- 15 The provision of the antifriction bearing between the plunger and presser foot reduces the resistance and strain due to friction, to a minimum, and to such extent, relieves the strain sustained by the threads 20 of the plunger in engagement with the head 2, to thereby reduce the danger of breakage at this point.

To releasably connect the plunger and presser foot for relative rotation, I prefer- 25 ably form a groove 13 circumferentially of the reduced end 8 of the plunger, and provide the socketed wall of the foot 6 with a tangentially-extending passage 14 intersecting the socket, to accommodate a taper pin 30 or cotter 15 which is passed through the tangential passage and lies tangentially across the groove 13.

This permits relative rotation between the plunger and presser foot, and to relieve the 35 taper pin or cotter of any strain exerted by the plunger when the device is in use, I prefer to locate the passage 14 at such a point above the upper ball race 9, and also, so locate the groove 13 at such a distance 40 from the inner end of the reduced portion 8 of the plunger 4, that when such inner end of the reduced portion 8 rests on the upper race, the groove will be located in the same plane with the passage 14, the 45 groove being sufficiently larger in diameter than the diameter of the pin 15 to permit a slight endwise movement of the plunger and the socket relatively to each other, to compensate for such slight wear as may take 50 place, without bringing the upper wall of the groove 13 into intimate contact with the pin 15 when the device is in use.

Should it become necessary to disassemble the device for inspection, lubrication, or 55 the replacement of broken parts, it is readily accomplished by simply driving out the taper or cotter pin 15, after which the presser foot 6 is slid off the reduced end of the plunger 4, and by inverting the foot, 60 the bearing drops out of the socket 7.

If the balls are broken, removal of the

bolt 11 will enable the operator to separate the races, remove the broken balls and substitute new ones therefor.

Should either the plunger or the foot be 65 broken, new parts may be readily substituted for the old parts without discarding the entire plunger and foot, and with a minimum of labor.

The sole 16 of the presser foot, may be 70 provided with an arcuate recess, as shown, to embrace and grip the edge of the tread of the rail and thus prevent rotation of the foot when the device is in operation, the high point of the arcuate groove lying in 75 substantial alinement with the axis of the plunger to focus the pressure within as small a compass as possible without developing a tendency to crack or break the rail at that point.

Changes may be made in the form and arrangement of the several parts set forth without departing from the spirit and scope 80 of this invention.

What I claim as new, is:—

In a rail bender, the combination with a bifurcated frame having a head; a threaded plunger passing through the head into the space embraced between the arms of the bifurcated frame; and means to turn the 90 plunger in either direction; of a presser foot having a socket formed in its inner end; the arms, and the sole of the foot adapted to engage the material to be treated; the operating end of the plunger being reduced and entered in the socket in the foot; a removable, antifriction bearing resting loosely on the bottom of the socket, and forming a thrust bearing for the end of the reduced portion of the plunger; the reduced portion having a circumferential groove; the socketed portion of the foot having a tangentially-extending passage intersecting the socket; a fastening pin of less diameter than the diameter of the groove, 100 and adapted to extend through the tangential passage, and tangentially along a portion of the circumferential groove, to releasably connect the foot and plunger for relative rotation, the length of the reduced portion of the plunger, the thickness of the antifriction bearing and the depth of the socket being so proportioned that the walls of the circumferential groove clear the fastening pin to avoid strain thereon in a direction axially of the plunger, the thickness of the antifriction bearing operating to space the inner end of the socket apart from the shoulder formed by reducing the plunger, to eliminate friction at that point. 110 115 120

SAMUEL V. TENCH.
